REGISTER RESETTING MECHANISM

Clement P. Griffith and Harvey E. Marvel, Fort Wayne, Ind., assignors to Bowser, Inc., Fort Wayne, Ind., a corporation of Indiana

Application November 14, 1945, Serial No. 628,458

4 Claims. (Cl. 222—33)

1

This invention relates to a register resetting mechanism. More specifically, it relates to an hydraulically operated resetting mechanism for a register such as is used in a gasoline dispensing pump.

Heretofore, it has been common practice to reset the register before each dispensing operation by rotating a crank which extends through the housing.

It is an object of this invention to provide a device for automatically resetting a register.

It is another object of this invention to provide an hydraulic device for resetting a register.

It is still another object of this invention to provide a register resetting mechanism which is operated by liquid from a pump at substantially the pump by-pass pressure.

It is yet another object of this invention to provide a register resetting mechanism which will complete the resetting operation once it is initiated.

Still another object of the invention is to provide a register resetting mechanism which begins to operate substantially as soon as the pump is started and completely resets the register before dispensing can be started under normal operating conditions.

Yet another object of the invention is to provide an hydraulic system which resets the register.

A further object of the invention is to provide a register resetting mechanism which returns to its initial position when the pump is shut down.

Still another object of the invention is to provide means for restoring the resetting mechanism to its initial position quickly and smoothly.

It is yet another object of the invention to provide power storing means to restore said resetting mechanism to its initial position when the pump is shut down.

Yet another object of the invention is to provide an hydraulic register resetting apparatus having a positive action.

These and other objects will become apparent from a study of this specification and the drawings which are attached thereto and made a part thereof and in which:

Figure 1 is an elevation of a gasoline dispensing pump chassis showing the pump, motor, air release, meter, register and hydraulic reset cylinder, sight glass and the connecting conduits.

Figure 2 is an elevation of the register and hydraulic cylinder partially in section as viewed from the left of Figure 1.

2

Figure 3 is a view partly in section and partly in elevation of the hydraulic cylinder, piston and valve.

Figure 4 is a section showing the number wheel aligning mechanism taken on the line 4—4 of Figure 2.

Figure 5 is a section of the apparatus of Figure 4, taken on the line 5—5 of Figure 4.

Figure 6 is a diagrammatic view of the check and relief valve.

Figure 7 is a diagrammatic view of the air separator and associated parts.

Referring to Figure 1 of the drawings, the numeral 1 designates the dispensing pump in general, having a base 3 and a frame 5. A cross-member 7 is welded to the frame above the base and supports an air separator 9 having a suction stub 11 for drawing gasoline from a storage tank (not shown). The air separator is of the conventional type used in a gasoline dispensing pump as shown in Patent Number 2,286,536, to Clement P. Griffith, having a suction chamber 10 and a float chamber 12. A pump 13 has a manifold 15 having one channel connected to the suction chamber (Figure 7) at 14 and another channel connected at 16 to discharge liquid into the separation chamber 18, at which point the gases and some spray are separated from the liquid and discharged through orifice 24 into float chamber 12, where further separation occurs and gases pass to the atmosphere through vent 20, while liquid passes back to the suction chamber 10 through the float controlled valve 22. A by-pass port 26, controlled by relief valve 28, is located in the air separator between chambers 18 and 10. A tubing connection 17 enters the side wall of the suction chamber of the air separator, while discharge conduit 29 communicates with the lower part of the separation chamber 18, through elbow 27.

Motor 19 operates the pump through the V belt 21, and the pulleys 23 and 25 attached to the motor and pump shafts, respectively.

Conduit 29 leads from the elbow 27 to the meter manifold 31 (Figure 6) which is divided into an inlet chamber 30, a check valve chamber 32 and a discharge chamber 34. Conduit 29 discharges into chamber 30, which is connected by a port 36 with chamber 32. A spring loaded check valve 38 closes the port, but opens in response to flow therethrough. The check valve is provided with a relief port 40 which is controlled by a relief valve 42 and closes in a direction opposite to that of the check valve.

Chamber 32 connects with the inlet port of

meter 35 and chamber 34 receives metered liquid discharged by the meter. Conduit 43 is connected to receive liquid from the chamber 34. A tube fitting 33 enters the chamber 30 of the manifold.

The meter 35 is suspended from a cross-member 37 by screws 39 (Figure 2) which pass through the positioning spacers 41.

The conduit 43 connects chamber 34 with a sight glass manifold 45 having two sight glasses 47. The sight glass manifold discharges into a conduit 49 having a fitting 51 which receives the usual dispensing hose 52 and nozzle 54.

The meter is connected by a shaft 53 to drive the resettable registers 55. The registering mechanism, indicated generally by numeral 58, rests upon supports 57, which are secured to the cross-member 37 by screws 39 and to the registering mechanism by studs 59 and nuts 61. Studs 59 are preferably welded to the base 63 of the registering mechanism.

The registering mechanism which is used is preferably that disclosed in the W. M. Carroll Patent No. 2,229,370, issued January 21, 1941, for Liquid dispensing apparatus. Accordingly, it is believed unnecessary to describe the mechanism in detail.

The rectangular side frames 67 of the mechanism 58 are fastened to each side of the base 63 by screws 69 and extend above the base. One of the side frames provides a bearing 70 for shaft 71 (Figure 4) and a similar bearing for shaft 73. (Shaft 71 corresponds to shaft 73 in the Carroll patent.) The other end of shaft 71 is supported by bearing 75 in bracket 77, the latter also providing a similar bearing for the other end of shaft 73. Shaft 71 is rotatable in the bearings and carries a sprocket 79 which is fixed to the shaft by pin 81. An idler sprocket 83 (Figure 2) is carried in a similar manner by shaft 73.

A register resetting drive gear 84 is loosely mounted on a hub 85 which is secured to the shaft 71 by key 87 and set screw 89 (Figures 4 and 5). The hub carries a pair of spaced projecting ears 91 into which are threaded the adjusting screws 93. The gear is provided with a projecting lug 95 which is received between the ears 91 and the adjusting screws 93. By loosening one screw and tightening the other, the relative angular positions of the shaft 71 and the gear 84 may be varied. This mechanism is used to adjust the alignment of the numerals on the registers with the fixed indicators on the dials all as disclosed.

A chain 97 (Figure 2) engages the sprockets 79 and 83. One end of the chain is hooked to a spring 99 which is anchored to a clip 101 welded to one of the spacers 41. The other end of the chain is fastened to the piston rod 139 of an hydraulic cylinder 101.

The cylinder is secured to the base 63 by screws 103 and nuts 105, which engage the upper flange 111 of the cylinder body 113. The cylinder body has a bore 115 extending up from the bottom and terminating in an inlet passage 117 having a neck 119 concentric with the bore depending into the cylinder. A flat valve face 121 is machined on the end of the neck and the sides of the neck are machined as at 123 to receive the recess 127 formed in piston 125. A boss 127 has a tapped inlet hole 129 which receives a tube fitting 131 (Figure 1). The inlet hole communicates with the inlet passage 117 of the cylinder. A bearing 133 and a counterbore 135 for a toroid packing 137 are provided in the top of the cylinder.

der for the piston rod 139. A cotter pin 141 passes through holes in the upper end of the rod and the lower link 143 of chain 97 to connect the rod with the chain.

The lower end of the rod 139 is provided with two reduced portions 145 and 147 (Figure 3). The portion 147 is threaded. A piston 125 is mounted on the threaded diameter 147 and is held in place against a washer 167, which seats on the shoulder formed at the juncture of the portions 145 and 147, by means of washer 171 and nut 173.

The piston is comprised of a leather 149 having an upturned lip 151 on its periphery which is adapted to seal against the cylinder wall 115, a metal follower 153 acting as a spreader inside the lip 151, a follower 155 of Bakelite or similar material of the same diameter as the metal follower placed on the opposite side of the leather, and a metal support plate 157 slightly smaller in diameter than the follower, all assembled as shown in Figure 3 and held in position by rivets 159 passing through holes 161 in each of the aforementioned pieces. The follower is in the shape of an annular ring. The leather, the Bakelite follower 155, and the support plate 157 have a centrally-located hole 163 to permit passage of the threaded end 147 of rod 139 and also have a series of aligned, radially spaced ports 165.

A pressure responsive valve 175 comprises valve body 177 which is circular in shape and has a concentric hole 179 acting as a bearing for the valve body on the rod portion 145. A counterbore 181, concentric with the hole 179, is formed in the lower part of the body and provides clearance over the washer 167 when the valve is in closed position. Two concentric sealing rings 183 and 185 are formed on the lower part of the body adjacent the counterbore and the bottom. The rings seat on the leather 149 and span the holes 165. A radially directed peripheral flange 187 is formed on the upper portion of the valve body and has a face 189.

A spring 191 thrusts against the face 189 and the top surface of the leather 149 to normally maintain the valve in its open position as shown in Figures 2 and 3. The hub 193 of the valve body is concentric with the hole 179 and, together with shoulder 195 on the shaft 139, limits the upward stroke of the valve. The hub slopes downwardly away from the center and joins the peripheral wall 197 which has a chamfer 199 on the inside at the top.

The neck 123 of the cylinder body 113 telescopes into the cavity 201 formed between the hub 193 and the wall 197. The surface 121 of the neck and the bottom surface 203 of the valve body form a metal to metal seal when the valve and piston are in the up position. The spring 99 overpowers spring 191 so that the piston is pulled against the valve to seat rings 183 and 185.

A cylinder head 205 having a discharge passage 207 and a threaded discharge outlet 209 to receive a tube fitting 211, is fastened to the bottom of the cylinder 113 by screws 213. A pad 214 on the inside of the head provides a stop for the piston on its downward stroke, the pad engaging the threaded end of the piston rod 139.

A tube 215 connects tube fittings 33 and 131 on the meter manifold 31 and the hydraulic cylinder 101 respectively. Another tube 217 connects the fittings 17 and 211 of the air separator 9 and the hydraulic cylinder head 205, respectively.

The motor 19 is started and stopped by a switch 231, which is actuated by a rod 233 attached to be actuated by the hose nozzle hook 235.

Operation

The dispensing pump shown is of the conventional type, having the hose 52 connected to the fitting 51 and the shut-off nozzle 54 at the opposite end.

When it is desired to deliver liquid, the nozzle is lifted from the hook 235 which is then actuated to in turn close switch 231 to start the motor 19 which drives the pump 13.

A short period of time elapses between the starting of the motor, the insertion of the nozzle tip into a fill pipe and opening of the nozzle valve to dispense liquid. During this period the pump is operating at substantially by-pass pressure and the fluid under by-pass pressure is utilized to reset the registers.

The piston 125, when the pump is inoperative, should occupy its uppermost position in the cylinder due to the action of the spring 99. The valve 175 should be closed and the seals 203—121 and 197—119 are established. However, should the valve not be closed, the seal 197—119 at least will be established.

When the switch 231 is closed, the motor 19 and pump 13 are started and, since the nozzle valve is closed, by-pass pressure of about 20 to 25 p. s. i. will be created in the pressure side of the pump which includes chamber 18 of the air release, pipe 29, and chamber 30 of the manifold 31, while a partial vacuum will exist in the air release chamber 10.

Since the upper end of the cylinder 113 is connected with the pressure chamber 30 and the lower end is connected with the partial vacuum chamber 10, a differential pressure will be applied to the valve 175 and it will close the ports if, for any reason, it has not already closed them. The pressure on the valve will move the piston and valve downwardly until the seal 197—119 is broken, whereupon the differential pressure will be applied to the entire piston and valve area. This pressure will hold the valve closed on the piston and will force the piston downwardly. This pulls the chain 97 down and rotates the sprocket 79 and the resetting shaft 71 in a clockwise direction (Figure 2). The shaft drives yoke 91, which in turn drives the reset gear 84. This movement is then transmitted to the resettable registers 55 through gearing which is not shown.

The described motion of the chain also rotates idler sprocket 83 and extends spring 99, building up power for retrieving the piston to its starting position when the pressure is relieved on the inlet side of the piston by shutting down the pump.

When this occurs, the pressure is relieved on the upper side of the piston and valve so that the valve spring 191 lifts the rings 183 and 185 off the leather 149, opening ports 165 to permit rapid passage of the liquid through the piston as the spring 99 pulls the piston upwardly to its initial position.

Thus the apparatus is restored to its initial position. The connection between the resettable registers and the resetting means normally includes a one-way ratchet drive, and this drive idles as the resetting gear 83 is rotated in the reverse direction by the spring 99.

The stops 121 and 214 limit the piston stroke and the adjustment mechanism 91, 93, etc., of

Figures 4 and 5 insures that the register wheels line up with their dial opening when the lower stop 214 is contacted by the piston.

It is obvious that various changes may be made in the form, structure and arrangement of parts without departing from the spirit of the invention. Accordingly, applicant does not desire to be limited to the specific embodiment disclosed herein primarily for purposes of illustration; but instead, he desires protection falling fairly within the scope of the appended claims.

What we claim to be new and desire to protect by Letters Patent of the United States is:

1. In a liquid dispensing apparatus, the combination of a resettable register, a pump, suction and discharge conduits connected to said pump, means for starting and stopping said pump, an hydraulic cylinder, means for connecting the outlet and inlet of said cylinder to said suction and discharge conduits respectively, a piston in said cylinder, means for connecting said piston to reset said register, a port in said piston, a valve adapted to control said port, said piston and valve having initial positions, a cylindrical sleeve, connected with said inlet and disposed coaxially within said cylinder, a sleeve on said valve adapted to telescopically and sealingly engage said first named sleeve when said valve is in its initial position, whereby liquid from said pump is applied to the valve to close the port when said pump is started and is thereafter applied to said piston as the seal between the sleeves is broken.

2. In a liquid dispensing apparatus, the combination of a resettable register, a pump, suction and discharge conduits connected to said pump, means for starting and stopping said pump, an hydraulic cylinder, means for connecting the outlet and inlet of said cylinder to said suction and discharge conduits respectively, a piston in said cylinder, means for connecting said piston to reset said register, a port in said piston and a valve adapted to control said port, said piston and valve moving between initial and operated positions, telescoping members on said valve and connected with said inlet, said members being constructed and arranged for telescopic and sealing engagement when said valve occupies its initial position, whereby liquid from said pump is applied to close said valve when said pump is started and is thereafter applied to said piston as the latter is moved from its initial position.

3. In a liquid dispensing apparatus, the combination of a resettable register, a pump, suction and discharge conduits connected to said pump, means for starting and stopping said pump, an hydraulic cylinder, means for connecting the outlet and inlet of said cylinder to said suction and discharge conduits respectively, a piston in said cylinder, means for connecting said piston to reset said register, a port in said piston and a valve adapted to control said port, said piston and valve moving between initial and operated positions, telescoping members on said valve and connected with said inlet, said members being constructed and arranged for telescopic and sealing engagement when said valve occupies its initial position, whereby liquid from said pump is applied to close said valve when said pump is started and is thereafter applied to said piston as the latter is moved from its initial position, and means for stopping said piston in the operated position.

4. In a liquid dispensing apparatus, the combination of a resettable register, a pump, suction

and discharge conduits connected to said pump, means for starting and stopping said pump, an hydraulic cylinder, means for connecting the outlet and inlet of said cylinder to said suction and discharge conduits respectively, a piston in said cylinder, means for connecting said piston to reset said register, a port in said piston and a valve adapted to control said port, said piston and valve moving between initial and operated positions, telescoping members on said valve and connected with said inlet, said members being constructed and arranged for telescopic and sealing engagement when said valve occupies its initial position, whereby liquid from said pump is applied to close said valve when said pump is 15

started and is thereafter applied to said piston as the latter is moved from its initial position, and yieldable means for opening said valve when said pump is stopped.
